UNITED STATES PATENT OFFICE.

PAUL MACGAHAN, OF PITTSBURGH, PENNSYLVANIA, ASSIGNOR TO WESTINGHOUSE ELECTRIC & MANUFACTURING COMPANY, A CORPORATION OF PENNSYLVANIA.

THERMOCOUPLE HEATING ELEMENT.

Application filed November 2, 1920. Serial No. 421,254.

To all whom it may concern:

Be it known that I, PAUL MACGAHAN, a citizen of the United States, and a resident of Pittsburgh, in the county of Allegheny and State of Pennsylvania, have invented a new and useful Improvement in Thermo-couple Heating Elements, of which the following is a specification.

My invention relates to electrical measuring instruments and particularly to thermo-couple heating elements for such instruments.

One object of my invention is to provide a heating element for a thermo-couple in which the heat may be concentrated at a predetermined portion of the element.

Another object of my invention is to provide a heating element, of the above indicated character, that shall not require excessive heating.

A further object of my invention is to provide a heating element for a thermo-couple that shall embody a portion which will heat to a greater degree than the adjoining portions when traversed by an electric current.

A further object of my invention is to provide a heating element, of the above indicated character, that shall embody a portion having a relatively low coefficient of thermal and electrical conductivity.

The heating elements that have been heretofore used for thermo-couples have been composed of conducting material having a relatively high inherent resistance. In order to develop a sufficiently high temperature at the junction of the thermo-couple, at a point intermediate the ends of the heating element, it has been necessary to overheat the heating element. Such overheating has often damaged the heating element.

In order to obviate the necessity for overheating the element, and in order to concentrate the heat at that portion of the element near which the thermo-couple is disposed, I provide a heating element having the two end portions thereof plated with conducting material having relatively low resistance to form two paths of relatively low resistance on each side of a predetermined portion of the strip at which the thermo-couple is to be disposed. The middle portion, having no low resistance conducting material associated therewith, retains its inherently high value of resistance.

Since the value of the resistance of each end portion, from the respective ends of the element to the portion at which the thermo-couple is disposed, comprises a path of low resistance, a relatively small amount of heat is developed in the end portions. Similarly, since the middle portion of the heating element, at which the thermo-couple is disposed, comprises a high resistance material, considerable heat is developed in that portion. Heat is thus concentrated at the point where needed and there is produced a more sensitive thermo-couple, which, when used in connection with a meter, renders the meter more efficient.

Figure 1 of the accompanying drawings is a diagrammatic view illustrating the connection to an electric circuit of a device embodying my invention.

Fig. 2 is a view, partially in elevation and partially in section, of a heating element embodying my invention, the heat gradient thereof being indicated diagrammatically.

Fig. 3 is a schematic view of a heating element as heretofore used, the heat gradient of such an element being indicated diagrammatically.

Referring to Fig. 1, a source 1 of electro-motive force supplies current to a circuit 2, that is to be measured by a thermal ammeter 3. The ammeter 3 comprises an indicating device 4 and a thermal unit 5. The thermal unit 5 comprises a heating element 6 and a thermo-couple 7 that are enclosed in an evacuated vessel 8.

Referring to Fig. 2, the heating element 6 comprises a conducting member 9 having an inherently high value of resistance, two portions of which are plated or otherwise covered with conducting material 10 of relatively low resistance from the respective ends of the element 9 to the portion 11, intermediate the ends, that remains uncovered. The low resistance material 10 may comprise a covering of copper, silver or gold, or of any other conducting material having a low coefficient of resistance. As illustrated by the dotted curve, the maximum value of the heat gradient curve occurs at the uncovered portion 11.

The reason for the form of the heat gradient curve that is illustrated in Fig. 2 is readily apparent since the two end portions, that are covered by the low resistance material 10, respectively form paths of rela-

tively low resistance. A relatively small amount of heat is therefore developed in the two end portions in comparison with the amount of heat that is developed in the middle portion 11.

Referring to Fig. 3, the dotted curve shown therein illustrates the heat gradient curve of heating elements that have been heretofore used for thermo-couple junctions. 10 It will be observed that the heating element is equally heated along the whole length thereof and that the temperature of the middle portion, at which the thermo-couple is disposed, will be considerably less than 15 the adjoining portions, since the heat developed at the middle portion must be employed to raise the temperature of the thermo-couple junction.

Although I have shown the device as 20 applied to a thermal ammeter, it is, of course, obvious that the heater may be applied to any thermal measuring instrument.

Also, I do not limit the heating element 25 embodying my invention to the specific form that is illustrated, nor to the specific metals mentioned, since it may be variously modified without departing from the spirit and scope of the invention, as set forth in 30 the appended claims.

I claim as my invention:

1. An article of manufacture comprising a single integral body of high-resistance conducting material and a filamentary coating 35 of relatively low-resistance material intimately engaging the same and extending therealong from each terminal thereof to a position spaced from the other coating to provide a concentrated heat zone spaced 40 from said terminals between the coatings.

2. An article of manufacture comprising a composite element in the form of an elongated strip or filament including a core of high-resistance conducting material and 45 coverings of relatively low-resistance material on the major portions of the element at either side of a relatively short uncovered portion of the strip.

3. An article of manufacture comprising

an elongated element of high-resistance conducting material and two tube-like bodies of relatively lower resistance conducting material surrounding the element and intimately engaging the same in slightly spaced end-to-end relation to each other to 55 provide a concentrated heat zone therebetween at a local position intermediate the ends of the element.

4. An article of manufacture comprising a composite element constructed entirely in the form of a filamentary strip or element including a base portion of relatively high resistance conducting material extending substantially throughout the length of the composite element and elongated filamentary 60 portions of relatively lower conducting material intimately joined thereto in spaced end-to-end relation to each other to provide a concentrated heat zone therebetween.

5. An article of manufacture comprising 70 a composite element constructed entirely in the form of a filamentary strip or element including a base portion of relatively high resistance conducting material extending substantially throughout the length of 75 the composite element and elongated filamentary portions of relatively lower conducting material intimately joined thereto in spaced end-to-end relation to each other and extending substantially to the outer ends of the composite element to provide a concentrated heat zone intermediate the ends of the composite element.

6. An article of manufacture comprising 80 an element of high-resistance conducting material and two tubular bodies of relatively lower-resistance conducting material surrounding the major portion of the element and intimately joined thereto in spaced end-to-end relation to each other to provide a relatively short concentrated heat zone therebetween at a local position intermediate the ends of the element.

In testimony whereof, I have hereunto 90 subscribed my name this 27th day of October 1920.

PAUL MacGAHAN.
